(Cl. D80—9)

To all whom it may concern:

Be it known that I, Richard M. Lottes, a citizen of the United States, residing at St. Louis, Missouri, have invented a new, original, and ornamental Design for an Article Display Rack, of which the following is a specification, reference being had to the accompanying drawings, forming a part thereof, in which:

Figure 1 is a front perspective view of an article display rack showing my new design;

Figure 2 is a top plan view thereof;

Figure 3 is an end elevational view thereof looking towards the left end of Figure 1;

Figure 4 is an end elevational view of the other end; and

Figure 5 is a rear elevational view thereof on a reduced scale.

I claim:

The ornamental design for an article display rack, substantially as shown.
